Primary Examiner—Melanie H Tung*Assistant Examiner*—Susan Moon Lee(74) *Attorney, Agent, or Firm*—John D. Gugliotta(57) **CLAIM**

The ornamental design for a portable pet feeder, as shown and described.

DESCRIPTION

FIG. 1 is a perspective view of a portable pet feeder shown assembled;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front perspective view of the portable pet feeder, shown in an open condition; and,

FIG. 9 is a partially exploded front perspective view thereof.
